UNITED STATES PATENT OFFICE

170,705

GUN CABINET

Clarence H. Krueger, Bovey, Minn.

Application September 8, 1952, Serial No. 21,375

Term of patent 14 years

(Cl. D33—19)

To all whom it may concern:

Be it known that I, Clarence H. Krueger, a citizen of the United States of America, residing at Bovey, in the county of Itasca, and State of Minnesota, have invented a new, original, and ornamental Design for a Gun Cabinet, of which the following is a specification, reference being had to the accompanying drawing, forming a part thereof.

I claim:

The ornamental design for a gun cabinet, as shown.

CLARENCE H. KRUEGER.
